(57) **CLAIM**

The ornamental design for an illuminated loudspeaker, as shown and described.

DESCRIPTION

FIG. 1 is a front view of an illuminated loudspeaker, showing a first illumination in the sequence showing the new design;

FIG. 2 is a second illumination thereof;

FIG. 3 is a third illumination thereof;

FIG. 4 is a fourth illumination thereof;

FIG. 5 is a fifth illumination thereof;

FIG. 6 is a sixth illumination thereof; and,

FIG. 7 is a seventh illumination thereof.

The evenly spaced broken lines illustrate portions of the design that form no part of the claimed design. The dash-dot broken lines represent the boundaries of the claimed design and form no part of the claimed design. The brighter arc-shaped areas enclosed in broken lines represent illuminated portions of the loudspeaker face that form no part of the claimed design. The remaining brighter arc-shaped areas represent illuminated portions of the loudspeaker face that form part of the claimed design.

The appearance of the animated illuminations sequentially transitions between the illuminations shown in FIGS. 1-7. The process or period in which one illumination transitions to another forms no part of the claimed design.
